US00D672841S

(12) **United States Design Patent**
Pelton

(10) **Patent No.:** **US D672,841 S**
(45) **Date of Patent:** **** Dec. 18, 2012**

(54) **KNIFE**

7,337,486 B2 3/2008 Tsuda et al.
7,360,267 B2 4/2008 Quenzi
D609,992 S 2/2010 Delaney

(75) Inventor: **Robert Young Pelton**, Bonsall, CA (US)

(73) Assignee: **DPX Ventures Limited**, Ras Al Khaimah (AE)

(**) Term: **14 Years**

(21) Appl. No.: **29/423,477**

(22) Filed: **Jun. 1, 2012**

(51) LOC (9) Cl. **22-02**

(52) U.S. Cl. **D22/118**

(58) Field of Classification Search D22/118;
D8/95-99; 7/158; 30/155, 157, 160-161

See application file for complete search history.
